UNITED STATES PATENT OFFICE.

FREDERICK HORNE, OF WILMSLOW, ENGLAND.

MEANS FOR THE PREVENTION OF CONDENSATION ON WINDOWS.

SPECIFICATION forming part of Letters Patent No. 507,731, dated October 31, 1893.

Application filed June 20, 1893. Serial No. 478,257. (No model.)

To all whom it may concern:

Be it known that I, FREDERICK HORNE, a subject of the Queen of Great Britain and Ireland, residing at Wilmslow, in the county 5 of Chester, England, have invented Improved Means for the Prevention of Condensation on Windows, of which the following is a specification.

The condensation of moisture upon windows, causes considerable inconvenience and loss, and this is more especially the case with shop windows, not only on account of the view of articles exhibited for sale being intercepted or in very cold weather entirely 15 hidden by the windows becoming "frosted," but also goods of various descriptions are in many cases irretrievably damaged by coming into contact with the moisture on the glass. This condensation (as is well known) is caused 20 by the warm moist atmosphere of the room or shop coming into contact with the cold glass of the window, causing it to gradually part with its moisture which becomes condensed upon the glass and in cold weather 25 frozen thereon.

The object of my invention is to entirely prevent this condensation and "frosting" (or to remove the same if already formed) which I propose to effect by passing a continuous 30 column of heated air over the interior surface of the window.

The manner in which my said invention is to be performed or carried into practical effect will be readily understood on reference 35 to the sheet of drawings hereunto annexed and the following explanation thereof.

The drawings represent, for the sake of illustration the application of my invention in the case where gas is used as a source of heat 40 for warming the air but other sources of heat may also be employed (as hereinafter explained) for the purposes of my invention.

Figure 1 on the drawings represents in elevation part of a shop or other window as seen 45 from the inside with my invention shown as applied thereto. Fig. 2 is a vertical section and Fig. 3 a horizontal section of the same.

a is part of the window frame and *b* is the ordinary window glass.

50 On the inside of the window I place a second sheet of glass *c* preferably thin and separated from the existing glass of the window

by a space of from two to three inches and (when gas or lamps are employed as a source of heat) extending to about two inches from 55 the bottom of the outside sheet. If hot air pipes are used, then the glass can extend to the bottom of outside sheet. If hot water pipes are employed, then the glass can extend to one inch from the bottom of outside sheet. 60

In the space between the two sheets of glass at the bottom of the window, I fix a gas pipe *d* fitted with burners equidistant (say two and a quarter inches) along its entire length (those burners known as "Bray's patent" answer very well) and also a band *e* of wire gauze (or other suitable material) bent in such a manner as to inclose the flame, thereby causing a greater quantity of air to be mixed with the gas, and producing a greater heat, with 70 less consumption of gas; but if desirable to utilize the gas for illuminating purposes, then the gauze can be dispensed with. If hot air be available, then I pass a pipe or pipes from the apparatus (in the place of the gas pipe *d*) 75 and having pierced the same at intervals, allow a sufficient quantity of hot air to pass upward between the two sheets of glass *b* and *c*. If hot water be the source desired to give the heat necessary, then a pipe or pipes 80 of such form and capacity, as are found most convenient, to the particular trade, can be used. If in country places, lamps are the only means available then I should adopt such lamps as would give a wide flame parallel to 85 the window.

The inside sheet of glass *c* may vary in width, a piece six inches wide being sufficient (under ordinary conditions as to draft, &c.) to maintain from two feet six inches to 90 three feet of the window perfectly clear of condensation. This would generally be equal to the "line of sight" of a man of medium height, standing on the pathway outside. The second or inner sheet of glass *c* is preferably 95 so adapted to the frame of the window, with buttons or other fastenings *f*, or hinged or otherwise so arranged that it can readily be removed for cleaning or other purposes when required.

100 The continuous current of heated air passing up between the two glasses *b* and *c* will cause the inner one to be kept at a temperature above that of the shop or room, and also

will so effectually ventilate that section immediately inside the window glass proper as in itself to prevent moisture in the air of the shop or room from coming into contact with 5 or condensing upon it, and "frosting" cannot then occur. If such does form during the 10 night or during cessation of using the "improved means" a very few minutes will suffice to evaporate all, and the window will be left clear and bright as a mirror. This improved means is almost imperceptible to persons outside.

I claim as my invention—

The improved means for the prevention of 15 condensation on windows consisting in the

combination with the glass of the window of an inner piece of glass parallel thereto, and apparatus for the admission into the space between the two of a continuous current of heated air substantially as hereinbefore described and illustrated by the drawings annexed.

In testimony whereof I have signed my name to this specification in the presence of two subscribing witnesses.

FREDERICK HORNE.
